UNITED STATES PATENT OFFICE.

EDWIN CLEARY, DECEASED, LATE OF LONDON, ENGLAND; BY ALFRED HUTCHISON,
ADMINISTRATOR, OF LONDON, ENGLAND.

BURNER FOR LIQUID FUEL.

Application filed January 3, 1923. Serial No. 610,543.

To all whom it may concern:

Be it known that EDWIN CLEARY, deceased, late a citizen of the United States of America, of London, England, has invented 5 a new and useful Improved Burner for Liquid Fuel, of which the following is a specification.

This invention relates to a modified form 10 of the burner for liquid fuel described in the specification of Letters Patent No. 1,381,080, and is designed to enable such burner to be used for heating inverted incandescent mantles.

According to this invention the burner 15 comprises a heat conducting plate that is heated at its underside by the burner proper and has extending from its underside a vertical gauze filled tube, to the lower end of which the liquid fuel is admitted and 20 through which extends the stem of a combined pricker and valve that controls the delivery of the fuel vapour from the upper end of the gauze filled tube to the nozzle or nipple from which a jet of vapour passes 25 into the injector tube, such injector tube being arranged on the upper side of the heat-conducting plate.

In the accompanying drawing, I have 30 shown how the said invention can be conveniently and advantageously carried into practice. In these drawings:—

Figure 1 is a side elevation and

Figure 2 a vertical central section of a 35 burner constructed according to the invention.

Figure 3 is a vertical central section illustrating a modification.

A is the heat-conducting plate, into the 40 lower side of which there is secured a tube B to receive a tubular filling of wire gauze C. Through the centre of the wire gauze there extends the stem D of a combined valve and pricker E, which engages in the bore of the nozzle F, that is screwed into a 45 socket on the upper side of the plate A.

In the burner shown in Figures 1 and 2, the lower part of the valve stem D is provided with a screw thread G which engages with a corresponding screw thread in the 50 inner part of a stuffing box H through which the valve stem D extends to the exterior. By providing the valve stem D with an operating handle J, it can be turned so as to open and close the passage through 55 the nozzle F by means of the needle E and

the conical valve E' below such needle. The lower end of the vertical tube B is mounted on a bracket K provided with a screw threaded tubular piece L adapted to screw into the inlet of the fuel container, the bore 60 of such tube communicating with the interior space of the tube B through a passage M. The piece L may have a tubular extension, or may fit into the mouth of a tube extending to the bottom of a liquid fuel container in the upper part of which an air pressure is maintained in a well known manner.

On the upper side of the heat conducting plate A there is mounted the U-shaped combined injector tube and mixing chamber, 70 one end part N of which is made bulbous and provided with one or more air inlets O, O. This end fits over the socket of the nozzle F and communicates through the vertical tube N' with the other limb P of the inverted U-tube, the lower end of which is drawn down on to the top of the plate A by means of screw threads on the tubular mixing chamber proper Q which is screwed 80 in from the underside of the plate A and is made with a collar or flange Q' for bearing against such plate. The lower end of the tube Q is closed by a perforated plate R of nickel, wire gauze or other suitable material. 85

The plate A is further provided with a cylindrical downward extension S having bayonet-slots S', S' to receive the projections on the supporting ring of an incandescent mantle as shown. The top of the U-tube N', 90 P is provided with a pin or projection T to receive a shade or reflector.

In the modification shown in Figure 3, the valve stem D is provided with a screw thread 95 at its upper end, such screw thread engaging a corresponding screw thread in the plate A and having one or more longitudinal slots 2 to permit the passage to the nozzle F of the oil vapour from the vertical tube B. In this burner, the air-inlet for 100 the injector-tube is made in the form of a separate piece 3 having a lateral opening 4. An annular cup 5 is arranged around the tubular piece L to receive methylated spirit or other suitable light hydrocarbon for use 105 in heating up the burner on starting.

What I claim is:—

1. A liquid-fuel burner for heating inverted incandescent mantles, said burner comprising a heat-conducting plate, a tu- 110

- 2
- 25 bular mixing chamber extending downwardly from said plate and having a flame orifice in its lower part, a second tube extending downwardly from the heat-conducting plate, an injector nipple arranged at the upper end of the second tube and delivering into an injector tube mounted above said heat-conducting plate, a valve-spindle extending axially through said second tube, 10 a needle valve on said spindle controlling the thoroughfare of said nipple, wire gauze packing in the space between the valve-spindle and the interior wall of the tube, means for closing fluid tight the lower end of 15 the second tube around said spindle, an oil-inlet branch at the lower end of the second tube and a U-shaped injector-tube mounted above the heat-conducting plate and connecting said mixing chamber and said nipple 20 and having an air inlet at the end next to the nipple.

2. A liquid fuel burner for heating inverted incandescent mantles, said burner comprising a heat-conducting plate, a tubular mixing chamber extending downwardly from said plate and having a flame orifice in its lower part, a second tube ex-

tending downwardly from the heat-conducting plate, an injector nipple arranged at the upper end of the second tube and delivering into an injector-tube mounted above said heat-conducting plate, a valve spindle extending axially through the second tube, a needle-valve on the end of said spindle and adapted to fit the thoroughfare of said nipple, an annular valve on said spindle adapted to coat with a valve seat at the upper end of the second tube, screw threads for controlling the axial movements of the spindle, wire gauze packing in the annular space between the valve spindle and the interior wall of the tube, means for closing fluid tight the lower end of the second tube around the spindle, an oil-inlet branch at the lower end of the second tube and a U-shaped injector-tube mounted above the heat-conducting plate and connecting said mixing chamber and said nipple and having an air inlet at the end next the nipple.

London, England, 21st December 1922.

ALFRED HUTCHISON,
Administrator of the estate of *Edwin Cleary*,
deceased.
